[57] **CLAIM**

The ornamental design of a multi-themed handicapped-accessible playhouse, as shown and described.

DESCRIPTION

FIG. 1 is a front, right and top perspective view of a multi-themed handicapped-accessible playhouse showing a new design in accordance with the present invention;

FIG. 2 is a back, left and top perspective view thereof;

FIG. 3 is a reduced rear view thereof;

FIG. 4 is a reduced left view thereof;

FIG. 5 is a reduced right view thereof;

FIG. 6 is a reduced front view thereof;

FIG. 7 is a rear elevational view of FIG. 3 with the fold down trays shown in a alternate position;

FIG. 8 is a right view of FIG. 5 with the fold down trays and door shown in a alternate position;

FIG. 9 is a left view of FIG. 4 with the fold down trays and door shown in a alternate position;

FIG. 10 is a front view of FIG. 6 with the fold down trays shown in a alternate position;

FIG. 11 is a reduced top plan view of FIG. 1 with the fold down trays and door shown in a alternate position; and,

FIG. 12 is a bottom plan view of FIG. 11; the door is disclosed fragmented for ease of illustration.

The broken line showing in FIG. 10 is for illustrative purposes only and forms no part of the claimed design.
